UNITED STATES PATENT OFFICE.

AUGUSTUS CICERO FELTON, JR., OF MACON, GEORGIA, ASSIGNOR TO NYE ODORLESS CREMATORY COMPANY, OF MACON, GEORGIA, A CORPORATION OF GEORGIA.

CREMATORY.

1,235,452.

Specification of Letters Patent. Patented July 31, 1917.

Application filed April 23, 1915. Serial No. 23,376.

To all whom it may concern:

Be it known that I, AUGUSTUS C. FELTON, Jr., a citizen of the United States, and a resident of Macon, in the county of Bibb and State of Georgia, have invented certain new and useful improvements in Crematories, of which the following is a specification.

My present invention is an improvement in furnaces for use in incinerating various refuse matter, and resides in the several novel details of construction, arrangement and operation to be now described in connection with the accompanying drawings which form a part of this specification, and in which—

Figure 1 is a front elevation.

Fig. 2 is a side elevation looking at one side.

Fig. 3 is a vertical longitudinal section taken therethrough substantially on line 3—3 of Fig. 4.

Fig. 4 is a vertical section taken therethrough substantially on line 4—4 of Fig. 3.

Fig. 5 is a vertical section taken therethrough substantially on line 5—5 of Fig. 6.

Fig. 6 is a vertical longitudinal section taken therethrough substantially on line 6—6 of Fig. 4.

Fig. 7 is a view similar to Fig. 5, with the upper part of the crematory removed, and illustrating a slightly modified form of air flues.

Fig. 8 is a top plan view, and

Fig. 9 is a horizontal section taken substantially on line 9—9 of Fig. 3.

Referring now to these figures, it will be seen that I provide a crematory consisting generally of a body in rectangular form, consisting of front and rear walls A and B, respectively, and side walls C and D, and having a vertical stack E rising from one side thereof adjacent the side wall C, the lower end of which stack, within the furnace, communicates with forwardly and rearwardly extending branch flues E' as best seen in Fig. 9, which in turn communicates with laterally projecting openings E'' at one side of the incinerating chamber F, the bases of which openings it will be noted from Fig. 4, are on a level with the grate section F' of the incinerating chamber, which gate section takes up one side of the chamber.

Over the incinerating chamber F is an

arch G, and at the front and rear of this arch are provided the vertical air flues H and I as plainly seen in Fig. 6, the arch G having a plurality of longitudinal air flues G' carried upon its under side by means of 60 suspension U-bolts G², and having their opposite ends respectively communicating with the vertical air flues H and I just mentioned, which latter will be seen from Fig. 6, to communicate at their lower ends by 65 openings H' and I', below the grate section F.

Supported upon the upper portions of the walls before mentioned, is a horizontal charging floor J, spaced above the arch G 70 so as to form an enlarged air space K therebetween, it being noted from Figs. 2 and 4 that the side walls C and D are provided with upper ventilators C' and D' respectively which constantly feed air into the 75 enlarged air space K during use of the furnace.

Referring again to Fig. 6, it will be noted that the extreme upper end of the vertical air flue H is separated from the air space 80 K by means of a plate H² and that this flue is provided with an intermediate damper H³. It will also be noted from the same figure, that the vertical flue I is provided with a plate I² below the adjacent ends of the 85 flues G', permitting the said flues to communicate with the air space K at the upper end of the flue I so that air may pass in the direction of the arrows in Fig. 6, through the flues G' and downwardly 90 through the flue H to the space beneath the grate section F' and consequently upwardly through the grate and thence laterally in the incinerating chamber F and outwardly 95 through the stack E.

The direction of movement of the air through the flues G' may be controlled by reversing the position of the plates H² and I², and by varying the length of these plates, the air may be caused to pass in one direction through certain of the flues G' and in the opposite direction through certain other flues, the vertical flue I being provided with a damper I³ similar to the damper H³ of the vertical flue H.

The charging floor J before mentioned, is provided at one side, opposite the stack E, with an opening covered by a door L, this opening communicating with a vertical chute L' for garbage, the lower end of which 110

communicates with an opening L^2 through the arch G above the grate section F' , the door L being controlled in its movement and in counterbalanced relation, by a flexible connection L^3 passing over a roller L^4 and provided with a counterbalancing weight L^5 .

Referring now again to the incinerating chamber F it will be seen that I provide a 10 solid shallow pan F^2 at the side of the grate section F' and depressed slightly below the level thereof, one end F^3 of which pan slopes from the main front opening F^4 which is closed by a laterally sliding outside door F^5 15 having a smaller door F^6 for a purpose to be hereinafter described. The opening F^4 to the pan F^2 , which extends through the front wall A , is aligned with an opening F^6 in the rear wall B , which opening is closed by 20 an outer door F^7 and leads into a pit M at the rear of the furnace, having at least one side wall M' as seen in Fig. 3, and having a roof M^2 which constitutes a driveway leading to the rear side of the charging floor J . This 25 driveway M^2 , as best seen in Fig. 8, is provided with an opening N communicating with the upper end of a chute N' as seen in Fig. 3, which is inclined downwardly and forwardly through the rear wall B and into 30 the rear of the incinerating chamber F above the rear end of the pan F^2 as best seen in Fig. 4, and below the arch G .

Within the pit M , and against its wall M' as clearly seen in Fig. 3, is arranged a drum or winch M^3 , from which a chain or other suitable flexible connection may be extended through the rear doorway or door opening F^6 and above the pan F^2 to and through the forward door opening F^4 when its laterally sliding door F^5 is moved to uncover the opening, it being noted from Fig. 3, as well as from Figs. 8 and 9 in particular, that the front wall A has a ledge A' at its outer surface extending therealong slightly 45 below the lower side of the door opening F^4 , and opposite, and in the same horizontal plane with, a coping A^2 parallel with the ledge, to receive removable supporting planks A^3 , the upper surfaces of which are 50 on a level with the lower edge of the door opening F^4 , and which thus form a convenient support for dead animals to which the chain or flexible connection is attached, operation of the winch or drum M^3 above mentioned, resulting in drawing the dead animal thus attached, into the pan F^2 .

The pan F^2 constructed as above described and arranged at one side of the grate section, thus retains the oils and juices from 60 animals drawn into the incinerating chamber by the means just previously described,

and also the night soil and excessively wet garbage which is introduced through the chute N' .

It will be noted that the charging floor J 65 has a substantial railing J' along its front and sides only, so that although this railing J' which is plainly seen in Figs. 3, 4, and 8, effectively holds the garbage or material dumped upon the charging floor J , until it 70 is introduced into the furnace through the chute L' , the driveway M^2 remains unobstructed in order that the vehicle transporting the garbage may be backed practically onto this discharging floor itself. 75

Through the front wall A , as plainly seen in Fig. 1, are arranged stoking and ash doors A^4 and A^5 respectively, opposite the grate section F' , and similar stoking and ash doors D^2 and D^3 are arranged in the 80 side wall D as plainly seen in Fig. 2.

Furthermore, by the use of dampers E^3 which, it will be noted from Figs. 3 and 9, are arranged within the flues E' leading from the openings E^2 to the stack E , the 85 draft may be regulated in any desired manner, and the heat and flame may be drawn from any part of the incinerating chamber to either of the floor openings E^2 , and the heat thus utilized where it is most desired. 90

I claim:—

1. A crematory including an incinerating chamber, an arch over the chamber having an air space thereabove and having a plurality of flues extending along its under side 95 and within the chamber, said chamber having air openings at its ends and vertical air flues leading upwardly from said air openings and with which said arch flues communicate at their opposite ends, a plate closing the upper end of one of said air flues above the arch flues, and a plate closing the other air flue at a point below the said arch flues, permitting communication of the latter at one end with the air space above the 105 arch.

2. A crematory including an incinerating chamber having a grate section, an arch over the said chamber and a charging floor 110 above the arch and forming an air space therebetween, said arch having a plurality of air flues extending along its under side, communicating at one end with the air space above the arch, and said incinerating chamber having a vertical flue opening at 115 its lower end below the said grate section and with which the opposite ends of the said air flues communicate.
